Attorney

UNITED STATES PATENT OFFICE.

CHARLES H. BENCKENSTEIN, OF VINTON, LOUISIANA.

TUBING SPACER.

Application filed April 4, 1921. Serial No. 458,307.

To all whom it may concern:

Be it known that I, CHARLES H. BENCKENSTEIN, a citizen of the United States, residing at Vinton, in the parish of Calcasieu and State of Louisiana, have invented certain new and useful Improvements in Tubing Spacers, of which the following is a full, clear, and exact description thereof.

My invention relates to tubing spacers, and an object thereof is to provide an apparatus of this character whereby the length of the tubing, and consequently the position of the working barrel of the pump, may be quickly and accurately adjusted; and whereby this adjustment may be made without the necessity of cutting any of the pipe sections.

Another feature of my invention resides in the provision of an adjusting mechanism so constructed that when the tubing has been adjusted to the desired length, there will be no liability of the pipe or tubing slipping.

It is often necessary that the position of the working barrel of a well pump be varied so that it will be properly positioned relative to the oil, water, or other liquid being pumped, and it therefore becomes necessary to vary the length of the tubing. The prior practice has been to cut a tubing section to the required length, thread it, and then secure it to the tubing. Obviously this is a very crude method, and is one that requires much time; and where the well is a great distance from a blacksmith's shop or foundry, it may be a question of days before the tubing can be hauled to a foundry, be cut and threaded, and returned to the well.

Further, as the length of the tubing has to be varied whenever the depth of the oil in a well changes, or when it is placed in another well, it is apparent that this old method necessarily resulted in the wasting of many pipe sections.

The present invention overcomes the above and other objections, as will appear from the description hereinafter.

Still another feature of my invention is to provide an apparatus of this character so

constructed that there can be no leakage of the oil or other liquid, through the adjusting mechanism.

In its more subordinate features, my invention consists in certain details of construction and peculiar combinations of parts, all of which will be fully described, specifically pointed out in the appended claims, and illustrated in the accompanying drawings, in which:

Figure 1 is an elevation of the tubing and the tubing spacer, the well casing being in section.

Figure 2 is a longitudinal sectional view taken through the axis of the tubing spacer; the rod spacer being in elevation.

Figure 3 is a cross-section taken on the line 2—2 of Figure 2, with the rod spacer, and sucker rod omitted for the sake of clearness.

Figures 4, 5, and 6, are detail views of the gripping wedges.

Numeral 1 indicates the well casing with the usual tubing 2 passing therethrough; and the tubing enclosing the sucker or pump rod 3. Numeral 4 refers generally to a rod spacer. The mechanism of the rod spacer is not shown in detail, as per se it forms no part of the present invention, and is the subject matter of a separate application, filed on or about February 10, 1921, Serial Number 443,841.

The tubing spacer apparatus includes a tubular member 5 which is approximately the length of one of the tube sections. The tubular member is accordingly broken away in the drawings. At the upper end of the tubular member, a coupling 6 is shown, which is for the purpose of coupling on another section of pipe.

To the lower end of the tubular member, is connected the element 7, which may be termed the top head. This top head has a relatively long cylindrical portion 8, projecting into the element 9, which may be termed the bottom head. The top head is screw threaded into the bottom head, as indicated by numeral 10.

A lock-nut 11 may be threaded onto the top head 7, for the purpose of preventing

relative movement between the top and bottom head, after the tubing has been secured in adjusted position.

For a portion of its length, the inner wall of the bottom head is tapered as designated by numeral 12, for the purpose of producing a wedging action, to be described.

Tapering arcuate gripping wedges 13, 14 and 15, are arranged in the interior of the bottom head, and are adapted to coact with the tapering wall thereof. In the particular embodiment of the invention illustrated, I show three of these wedges, the wedges 13 and 14 biting upwardly, and the wedge 15 biting downwardly. Obviously any number of these gripping wedges may be employed, and in so far as the invention is concerned, it is immaterial what character of gripping surface is provided on the wedges, though it is preferable to have the greater part of the gripping surface acting upwardly, as the weight of the tubing is exerting a force downward.

The operation of the apparatus thus far described is as follows:

Assume the various elements to be in the position shown in Figure 2, that is in locked position. In order to vary the length of the tubing, the lock-nut 11 is first released, and the bottom head is then unscrewed sufficiently to relieve the pressure exerted on the gripping wedges by the lower cylindrical portion 8 of the top head. The wedges are thus released, and the pipe or tubing 2 is free to be moved to any desired position in the tubular member 5. After the pipe has been moved to the desired position to give the correct length of tubing, the bottom head 9 is screwed up, whereby the lower portion 8 of the top head 7 is drawn downwardly, exerting a force on the gripping wedges, and by reason of the tapering surface 12 of the bottom head coacting with the tapering surfaces of the wedges, the gripping wedges are caused to bite into, and securely hold, the pipe in adjusted position.

It is apparent that with the apparatus thus far described, a portion of the oil, or other liquid, drawn up through the pipe 2, would leak through the adjusting mechanism.

In order to prevent this leakage, the lower interior portion of the bottom head is made cylindrical, and a portion thereof is screw threaded. Any desired type of packing, indicated by numeral 17, is inserted in the cylindrical portion, around the pipe 2, and is wedged into place by the packing gland 16, which is threaded into the bottom head, as shown. The adjusting mechanism is thereby made leak-proof.

I have shown the rod spacer in connection with the tubing spacer, and it is contemplated that they be used in conjunction,

though of course the invention is not limited to such use.

While I have shown and described the preferred construction and arrangement of the several elements employed, it is obvious that the invention is susceptible to considerable modification therein, and I therefore reserve the right to resort to all such legitimate changes as may be fairly embodied within the spirit and scope of the invention, as claimed.

Having fully described my invention, what I claim as new and desire to secure by Letters Patent is:

1. A tubing spacer mechanism including relatively movable top and bottom heads through which the well tubing is adapted to pass, an integral annular member formed on one of the heads and projecting into the interior of the other head, gripping means coacting with one of said heads and with the annular member of the other head to grip the tubing, and means provided in said tubing spacer for rendering the same leak proof.

2. A tubing spacer mechanism including relatively movable top and bottom heads through which the well tubing is adapted to pass, means for locking the top and bottom heads against relative movement, gripping means coacting with said heads, and adapted to grip the tubing, and means provided in said tubing spacer for rendering the same leak-proof.

3. A tubing spacer mechanism including relatively movable top and bottom heads through which the well tubing is adapted to pass, an annular member carried on one of the heads and projecting into the interior of the other head, gripping means coacting with one of said heads and with the annular member of the other head to grip the tubing, packing arranged in the interior of the bottom head around the tubing, and a gland for engaging said packing.

4. A pipe spacer mechanism including relatively movable top and bottom heads through which the pipe is adapted to pass, a portion of the interior of the bottom head having a tapering wedging surface, gripping means coacting with the gripping surface and adapted to grip the pipe, the lower portion of the interior of the bottom head being cylindrical, and packing arranged in said cylindrical portion.

5. A tubing spacer mechanism including relatively movable top and bottom heads, through which the tubing is adapted to pass, a portion of the interior of the bottom head having a tapering wedging surface, gripping means coacting with the wedging surface and adapted to grip the tubing, the lower portion of the interior of the bottom head being cylindrical, a shoulder formed between

the tapering portion and the cylindrical portion, a gland screw threaded into the bottom head, and packing arranged between the shoulder and the gland.

5 6. A pipe spacer mechanism including relatively movable top and bottom heads, through which the pipe is adapted to pass, means for locking the top and bottom heads against relative movement, a portion of the

10 interior of the bottom head having a taper-

ing wedging surface, gripping means coacting with the wedging surface and adapted to grip the pipe, the lower portion of the interior of the bottom head being cylindrical, a shoulder formed between the tapering portion and the cylindrical portion, a gland screwthreaded into the bottom head, and packing arranged between the shoulder and the gland. 15

CHARLES H. BENCKENSTEIN.
